US0D1004631S

(12) **United States Design Patent** (10) **Patent No.:** **US D1,004,631 S**
(45) **Date of Patent:** **** Nov. 14, 2023**

(54) **CONCRETE ROLLER**

- (71) Applicant: **Steelike, Inc.**, Springfield, VA (US)
- (72) Inventor: **William Thomas Kulish**, Fairfax, VA (US)
- (73) Assignee: **Steelike, Inc.**, Springfield, VA (US)
- (**) Term: **15 Years**
- (21) Appl. No.: **29/755,965**
- (22) Filed: **Oct. 23, 2020**
